Attorney

UNITED STATES PATENT OFFICE.

HARRISON O. BLAISDELL, OF BROOKLYN, NEW YORK, ASSIGNOR TO UNDERWOOD
ELLIOTT FISHER COMPANY, OF NEW YORK, N. Y., A CORPORATION OF DELAWARE.

TYPEWRITING MACHINE.

Application filed November 18, 1925. Serial No. 69,761.

This invention relates to means for quickly collating work-sheets in typewriting machines used in some systems of bookkeeping where each time a bill is typed, it is first collated with a ledger-sheet, and then both sheets are fed around the platen to the typing line, the items typed upon the bill-sheet being manifolded in proper line-space order for posting upon the ledger-sheet.

10 In the patent to Dennis, No. 1,180,250, dated April 18, 1916, means are shown where two sheets may be collated relatively to each other and to the typing line by the use of a table at the introductory side of the platen having 15 line-space readings along the edge thereof to which numerals previously printed line-space distances apart along the edge of the rear face of the work-sheets are aligned to relatively displace the sheets, the relative displacement being predetermined by a reading of other numerals printed along the edges of the front faces of the sheets indicating the line-space position of each sheet to be simultaneously typed. These sheets must be 20 aligned with one another, and there must be alignment with the typing line and with a numbered scale line on the edge of the collating table. It therefore involves effort on the part of the operator to avoid mistakes and 25 produce neatly and evenly typed records on the covered-up ledger-sheet.

In the patent to Hilsee, No. 1,426,077, dated August 15, 1922, the numbering at the edges of the work-sheets is wholly eliminated and 35 for the class of posting described by Hilsee where single-line entries have a fixed daily or monthly line-space position on the ledger or record sheet, the substitution of the sheet-end gage for uniformly collating the ledger-sheets for a daily or monthly single line entry simplifies the Dennis mode of operation, and greater speed and accuracy are secured, where a large quantity of single-line daily and monthly records are to be posted. If, 45 however, the character of the posting requires a second collation of the same record-sheet during a daily or monthly interval, it is obvious that the sheet-end gauge employed for the first collation of the record-sheet could 50 not be employed for the subsequent collating operation, without a corresponding readjustment of said gage, or the readjustment of the platen-stops; or the operator must first collate the sheet by the end gage setting and

then manually advance the sheet and platen one line-space distance before the statement or bill sheet is collated at the leading-in stops at the rear of the platen. And while the Hilsee device is mechanically effective for a class of ledger posting requiring single-line entries only at fixed intervals, the employment of the device for a class of mixed postings constantly varying during a fixed interval of time would require an additional manually-collating operation that would confuse the operator, as it would involve properly collating work-sheets that require dissimilar collating operations. Furthermore, in such a method of collating mixed work-sheets, some of which would require more lines than others, the blank spaces on the ledger-sheets would have to be made wide enough to receive the maximum number of typed lines required on any one of the bill-sheets for a daily or monthly interval, which, of course, would render the printed forms cumbersome and wasteful of space.

The present invention presents improvements over both Dennis and Hilsee, by eliminating the printing of all numerals along the edges of the rear faces of both work-sheets, and having numerals printed along one edge of the front face of the ledger or work sheet only, numerals that do not co-operate with scale-readings on the collating table in the manner of Dennis or require the daily and monthly adjusted rear-end sheet gage of Hilsee. It is the purpose of the present invention to provide the face of the ledger-sheet with marginal numerals beginning at "1" at the top of the sheet, for the purpose of numerically indicating line-space positions, down the ledger-sheet, to enable the operator to see at a glance the numbered position of the next line to be typed thereon. A collating table at the rear of the platen is provided with a collating plate or sheet-end scale having serially-numbered lines thereon readable by the eye, or progressively-numbered irregularities discernable by the sense of touch. The ledger-sheet is forced around the rear of the platen and under the cast-off feed-rolls. If a reading of the sheet indicates that the line 6 is the next line thereon to be typed, the rear end of the sheet is aligned to the scale-reading on the collating plate marked 6, or a special index line upon the sheet aligned to a predetermined line on said scale, or the

bottom edge of the work-sheet forced into a groove of a corrugated collating plate and the feed-rolls restored to hold the sheet in feeding relation against the platen. The invention or statement sheet that is without side-edge numerals of any character is collated over the ledger-sheet with the carbon-inlay and with the leading-in edges adjusted at the bite of the feed-rolls and platen. The platen 10 may be provided with the usual Underwood sheet-inserter, where a lever is swingable to sweep the platen forwardly a dimension equal to the distance around the under side of the platen from the feed-rolls to the typing line 15 plus the depth of the printed heading on the work-sheet, the sweep of the platen-rotating lever being determined by stops, and which stops when once adjusted are never changed except where a change occurs in the printed blank form of the work-sheet. The forward sweep of the lever carries both work-sheets to the typing line thereon to receive the single-line entry.

If the ledger-sheet typed upon at line 6, as just described, is subsequently to be typed upon line 7, it is reinserted at the rear of the platen as before, to align the bottom edge of the sheet to the "7" scale-reading on the collating plate, and the sheet is collated relatively to the feed-roll position without printing numerals along the edge of the rear face of the sheet and without the mental effort required in aligning numerals upon the work-sheet to dissimilar numerals at the edge of the collating table of Dennis or any change in the mode of operation, as required by Hilssee when two or more lines are typed within a daily or monthly interval. The present organization of the parts provides a novel mode of operation for collating the two work-sheets that is uniformly the same regardless of the relative displacement of the two sheets when collated, regardless of the number of consecutive entries made within a predetermined daily or monthly interval of time, and requiring no readjustment of the work-sheet-gaging element at any time.

Other features and advantages will herein-after appear.

50 In the accompanying drawings,

Figure 1 is a front elevation showing the invention applied to an Underwood standard typewriting machine, having a sheet-inserter attached thereto.

55 Figure 2 is a cross-sectional view, in elevation, through the center of the platen of the machine.

Figure 3 is a perspective view showing a flat form of collating plate.

60 Figure 4 is a perspective view showing another form of collating plate, where corrugations are formed therein to provide stop-ribs for the lower edge of the sheet instead of aligning said edge to lines upon the plate 65 shown in Figure 3.

This invention is illustrated as applied to an Underwood typewriting machine, which has a platen 10 and a sheet-inserting device mounted on the platen-axle 11. The sheet-inserter has a handle 12 pivotally mounted on the platen-axle and a pawl 13 mounted thereon designed to engage with a ratchet 14 fast to the platen-axle. There are also provided means for limiting the sweep of said handle, said means consisting of a movable plunger 15, which is radially mounted to interlock with holes in a stationary plate 16, pivoted on the platen-axle 11, as more clearly shown in the patent to Henning, dated May 5, 1914, No. 1,095,573.

According to the method of handling the work in this invention, a ledger-sheet 17 is inserted at the rear of the platen to rest upon a rear paper-table 18, and squared against a long sheet-edge guide 19, said guide being slidably mounted on screws 20, engaging with elongated slots 21 in said guide. The ledger sheet is inserted upside down, in the usual manner, and one form of the invention may be provided with an indexing line 22 at the back thereof, positioned to align with any one of a series of lines designated by the numeral 23 marked on a collating plate 24. Said plate is adjustably secured by screws 25, which pass through slots 26 and thread into the table 18, so that the lines on the plate will be a continuation of line-space distances from the typing line. It will be understood that previously to inserting the ledger-sheet around the platen, the regular feed-rolls 27 are released by means of a handle 28, to permit the free sliding insertion of the sheet. Said feed-rolls are pivotally mounted on a shaft 29, and may be released by means of a second shaft 30, operatively connected to the finger-piece 28 by means of a link 31.

After positioning the ledger-sheet, the feed-rolls are rendered operative, and then a bill-sheet 32, together with an associated sheet of carbon 33, is inserted in back of the ledger-sheet, over the rear table, and is forced downwardly against the rear feed-rolls. Since the feed-rolls are in their operating position, it will be clear that if the handle 12 is swung rearwardly, both the ledger-sheet and the bill-sheet will be rotated with the platen.

The ledger-sheet form is provided with a series of lines 34 printed upon the front face thereof line-space distances apart to correspond with the line-spacing of the platen. The lines are consecutively numbered starting at the top of the sheet with the numeral "1". Previously to inserting the sheet around the platen, a reading is taken of the last line of typing on the sheet, so as to ascertain the number for the next line to be typed thereon. Then the sheet is inverted and is reversed, so that the front thereof will face the rear table, and the line 22 on the back of the sheet is indexed to a line on the collating plate num- 125 130

bered correspondingly to the number of the line on the work-sheet upon which it is desired to type.

According to one form of the invention, the 5 collating plate 24 may be of aluminum, having lines 35 engraved or etched thereon, the lines being spaced distances corresponding to the line-spacing on the ledger-sheet. At the outer end of each line, preferably at the right-hand side of the plate, there are provided identification numbers 36, which are numbered from top to bottom for a length equivalent to the total length of the ledger-sheet. In the present form there are provided fifty- 10 two line-spaces.

According to another form of the invention, the collating plate 37 may be provided with corrugations or grooves 38, the numbers 36 being stamped into the grooves. One advantage of this form of the invention is, that the trailing edge of the ledger-sheet may be readily aligned with the corrugations by the sense of touch preparatory to squaring the sheet against the gage 19.

25 In the Underwood machine there is provided a platen-frame having end plates 39, in which the platen-axle 11 is journaled. The rear paper-table 18 is secured to a cross-bar 40, which is, in turn, secured, by means of screws 30 41, to the end plates 39.

According to one form of the invention, the collating plate 37 is removably secured to the paper-table by a rolled edge 42, designed to snugly fit over the rolled upper edge 43 of said table. It will be understood that the plate 24 may be provided with a rolled edge similar to the plate 37, or that the latter may be provided with slots similar to the slots 26 in the plate 24.

40 Referring more particularly to Figures 1 and 2, in which the work-sheets are shown before and after operation of the sheet-insertor, it will be noted that the sheets are respectively shown in full and dot-and-dash lines, the latter showing the position of the sheets for receiving typing theron by means of type-bars 44.

It is the preferred form of the invention 50 that the line 22 be omitted and that no printing whatever be required upon the back of the ledger-sheet, and that where the form of collating plate shown in Figures 1 and 2 or the corrugated form of plate shown in Figure 4 is employed, the bottom edge of the ledger-sheet 55 will be aligned to either form to establish the collated position of the sheet to the next line to be typed. If, in the printing of the ledger-sheet, gage-pins are used in the printing press to bear against the bottom edge of the sheet, the spaced-off numbered lines on the sheet will be accurately printed relatively to the bottom gaged edge, and the subsequent alignment of this bottom edge to the accurately adjusted collating plate will be productive of neat, uniformly line-spaced typing

upon the covered-up ledger-sheet, the corrugated form shown in Figure 4 being especially advantageous by enabling the operator to press the rear edge into a groove to register with a rib separating two adjacent grooves 70 which affords a speedier alignment of the work-sheet than where said edge is brought into alignment with a line on the face of the collating plate. If the corrugated collating plate were wider than that shown in the 75 drawings, to correspond practically to the width of the ledger-sheet, the alignment of the bottom edge of the sheet to the ribs formed by the corrugations would also square 80 the ledger-sheet to the typing line and take 85 the place of the long sheet edge gage 19.

It will be noted that the numeral designations indicating line-space distances upon the collating plate are numbered from "1" at the top down to "52" at the rear of the platen. 90 Reading the number of the next line to be typed upon the face of the ledger-sheet and then adjusting the bottom edge to a similar scale-reading on the collating plate is a very simple mode of operation compared to the operation required by Dennis where the sheet-edge numerals are continually shifting in relation to the numbers on the fixed collating table, taxing the mind of the operator to properly align two rows of mixed figures that 95 in themselves do not suggest the actual line-space positions in consecutive order, as employed in the present invention.

Variations may be resorted to within the 100 scope of the invention, and portions of the improvements may be used without others.

Having thus described my invention, I claim:

1. The combination with a typewriting machine having a revoluble platen and a rear table at the introductory side of the platen for a work-sheet, of a plate mounted on the rear table and provided with corrugations line-space distances apart for gaging the trailing edge of the work-sheet when inserted around the platen. 105

2. The combination with a typewriting machine having a revoluble platen and a rear table at the introductory side of the platen for a work-sheet, of means for gaging the work-sheet including a corrugated plate mounted on the rear table and operative to receive the trailing edge of the work-sheet when inserted around the platen, the corrugations on the plate being consecutively numbered from top to bottom, and each numbered corrugation corresponding to a numbered printing line on the work-sheet. 110

3. In a typewriting machine, in combination with the platen and the feed-rollers associated therewith, means for so collating a ledger-sheet and a bill-sheet relatively to each other that the matter typed upon the bill-sheet will be manifolded upon any desired line-space on said ledger-sheet, said means 120

including a universal bottom-end-printing-line finder having a scale located at the introductory side of the platen and having a series of graduations line-space distances apart and numbered in the same order as the succession of numbered line-spaces on the face of the ledger-sheet, whereby alignment of the bottom of the ledger-sheet with any one of said numbered graduations will predetermine the positioning of the correspondingly numbered line-space on the face of the ledger-sheet at the printing line, a gage for the leading edge of the bill-sheet, there being a carbon inserted between the sheets, and means for sweeping the platen and therewith the sheets through a predetermined fixed distance to present the desired space at the printing line.

4. In a typewriting machine, in combination with the platen and the feed-rollers associated therewith, means for so collating a ledger-sheet and a bill-sheet relatively to each other that the matter typed upon the bill-sheet will be manifolded upon any desired line-space on said ledger-sheet, said means including a universal bottom-end-printing-line finder having a scale located at the introductory side of the platen and having a series of graduations line-space distances apart and numbered in the same order as the succession of numbered line-spaces on the face of the ledger-sheet, whereby alignment of the bottom of the ledger-sheet with any one of said numbered graduations will predetermine the positioning of the correspondingly numbered line-space on the face of the ledger-sheet at the printing line, a gage for the bill-sheet so disposed as to position the latter so that the corresponding spaces on the ledger and bill sheets to be typed are in alignment, there being a carbon inserted between the sheets, and means for sweeping the platen and therewith the sheets through a predetermined fixed distance to present the desired space at the printing line.

5. In a typewriting machine, in combination with the platen, means for collating a work-sheet so as to present any desired space at the printing line, including a universal bottom-end-printing-line finder, said finder including a scale located at the introductory side of the platen and having a series of graduations line-space distances apart and numbered in the same order as the succession of numbered line-spaces on the face of the work-sheet, whereby alignment of the bottom of the work-sheet with any one of said numbered graduations will predetermine the positioning of the correspondingly numbered line-space on the face of the work-sheet at the printing line, and means for sweeping the platen and therewith the sheet through a predetermined fixed distance to present the desired space at the printing line,

said distance being equivalent to the heading at the top of the sheet.

6. In a typewriting machine, the combination with a rotatable platen, of means for gaging the lower edge of a work-sheet to predetermine a line-position thereon for typing, said means including a table at the introductory side of the platen having a corrugation within which the bottom edge of the work-sheet is aligned.

7. In a typewriting machine, the combination with a rotatable platen, of means for gaging the lower edge of a work-sheet to predetermine a line-position thereon for typing, said means including a table at the introductory side of the platen having a corrugation within which the bottom edge of the work-sheet is aligned and extending sufficiently across the table parallel with the platen to operate also to square the work-sheet relatively to the typing line.

8. In a typewriting machine, the combination with a rotatable platen, of means for variably gaging the lower edge of a work-sheet to predetermine a line-position thereon for the next line of typing, said means including a table at the introductory side of the platen having a series of corrugations within which the bottom edge of the work-sheet is progressively aligned.

9. In a typewriting machine, the combination with a rotatable platen having a table at the introductory side thereof, of a universal bottom-end-printing-line finder permanently secured to said table and operative to variably gage the lower edge of a work-sheet, said finder including a plate having graduations to which the bottom edge of the work-sheet is alignable to establish progressive typing-line positions for the work-sheet, said graduations being consecutively numbered from the top to the bottom of the table.

10. In a typewriting machine, the combination with a rotatable platen having a paper-table at the rear thereof, of a universal bottom-edge-printing-line finder secured to said table to variably gage the lower edge of a work-sheet for a typing position, said finder including a plate having a graduated numbered scale, the numbering on said scale being in the same order as the succession of numbered line-spaces on the face of said work-sheet.

11. In a typewriting machine, the combination with a rotatable platen having a paper-table at the rear thereof, of a universal bottom-edge-printing-line finder secured to said table and operative to variably gage the lower edge of a work-sheet for a typing position, said finder including a plate having a graduated numbered scale, the numbers of said scale increasing from the top to the bottom of said plate, whereby alignment of a mark

on the rear of a work-sheet with any one of said numbered graduations will predetermine the positioning of the correspondingly numbered line-space on the face of the work-sheet

5 at the printing line.

12. In a typewriting machine, the combination with a rotatable platen having a paper-table at the rear thereof, of a universal bottom-edge-printing-line finder permanently secured to the table for variably gaging one work-sheet for relative displacement with another work-sheet prior to being fed to a uniform typing position on the platen, said finder including a collating plate having 10 spaced-off line-space distances in the form of progressively-numbered lines thereon, the numbers being in the same order as the succession of numbered line-spaces on the face of the work-sheet, and to which lines the 15 lower edge of the work-sheet is aligned according to a predetermined plan to advance said work-sheet around the platen prior to the collation of the other work-sheet.

13. In a typewriting machine, in combination with the platen and the feed-rollers associated therewith, means for so collating a ledger-sheet and a bill-sheet relatively to each other that the matter typed upon the bill-sheet will be manifoldded upon any desired 20 line-space on said ledger-sheet, said means including a universal bottom-end-printing-line finder having a scale located at the introductory side of the platen and having a series of graduations line-space distances 25 apart and numbered in the same order as the succession of numbered line-spaces on the face of the ledger-sheet, whereby alignment of the bottom of the ledger-sheet with any one of said numbered graduations will 30 predetermine the positioning of the correspondingly numbered line-space on the face of the ledger-sheet at the printing line, said graduations including corrugations parallel with the platen and against the ribs of which the 35 bottom edge of the ledger-sheet may be aligned to true the sheet with respect to the printing line, a gage for the bill-sheet so disposed as to position the latter so that the 40 corresponding spaces on the ledger and bill 45 sheets to be typed are in alignment, there being a carbon inserted between the sheets,

and means for sweeping the platen and therewith the sheets through a predetermined fixed distance to present the desired space at the printing line.

55

14. In a typewriting machine, in combination with the platen, means for collating a work-sheet so as to present any desired space at the printing line, including a universal bottom-end-printing-line finder, said finder 60 including a scale located at the introductory side of the platen and having a series of graduations line-space distances apart and numbered in the same order as the succession of numbered line-spaces on the face of the 65 work-sheet, whereby alignment of the bottom of the work-sheet with any one of said numbered graduations will predetermine the positioning of the correspondingly numbered line-space on the face of the work-sheet at 70 the printing line, said graduations including corrugations parallel with the platen and against the ribs of which the bottom edge of the work-sheet may be aligned to true the sheet with respect to the printing line, and 75 means for sweeping the platen and therewith the sheet through a predetermined fixed distance to present the desired space at the printing line, said distance being equivalent to the heading at the top of the sheet.

80

15. In a typewriting machine, the combination with a rotatable platen having a paper-table at the rear thereof, of a universal bottom-edge-printing-line finder permanently secured to the table for variably gaging 85 one work-sheet for relative displacement with another work-sheet prior to being fed to a uniform typing position on the platen, said finder including a collating plate having spaced-off line-space distances in the 90 form of progressively-numbered lines thereon, the numbers being in the same order as the succession of numbered line-spaces on the face of the work-sheet, and to which lines the lower edge of the work-sheet is aligned 95 according to a predetermined plan to advance said work-sheet around the platen prior to the collation of the other work-sheet, and a gage for said other work-sheet to position the same with respect to said first sheet 100 so as to properly align the said sheets.

HARRISON O. BLAISDELL.
